UNITED STATES PATENT OFFICE.

WILLIAM W. WOODRUFF, OF CANTON, MISSISSIPPI.

SANITARY MOUTHPIECE.

1,019,288.

Specification of Letters Patent. Patented Mar. 5, 1912.

Application filed July 8, 1911. Serial No. 637,489.

To all whom it may concern:

Be it known that I, WILLIAM W. WOODRUFF, a citizen of the United States, residing at Canton, in the county of Madison and 5 State of Mississippi, have invented new and useful Improvements in Sanitary Mouthpieces; of which the following is a specification.

This invention relates to a sanitary 10 mouthpiece for telephone instruments, speaking tubes and other devices, and the primary object of the invention is to provide a chamber or receptacle around and in communication with the interior of a mouth- 15 piece and filled or supplied with a suitable antiseptic salt, chemical compound, or germicide of a slightly volatile quality and having the characteristic of giving off sufficient moisture to slightly dampen the inner 20 surface of the wall of the orifice, so that if by chance any germ which the fumes of the germicide do not kill, be deposited on the said inner surface it will be held against inhalation by the user of the mouthpiece.

25 A further object of the invention is to provide a mouthpiece with a germicide holding chamber between imperforate outer and perforate inner shells in continuous relation at their outer terminals and spaced at 30 their inner terminals to form an inner feed or supply opening for the chamber, and also to embody as a part of the mouthpiece a combined chamber closing and mouthpiece attaching means of a conveniently operative 35 structure.

With these and other objects and advantages in view, the invention consists of the construction and arrangement of the several parts which will be more fully hereinafter 40 described and claimed.

In the drawing: Figure 1 is a sectional perspective view of a telephone transmitter illustrating one application of the improved mouthpiece. Figs. 2 and 3 are detail sectional perspective views of the parts of the mouthpiece shown separated.

The numeral 5 designates the outer shell and 6 the inner shell of the mouthpiece, the said shells being formed of suitable material 50 and preferably continuous at the outer terminal of the piece and spaced to provide an inlet or supply opening 7. The material of which the shells are formed is bent or otherwise shaped or formed to produce the said inner and outer shells 5 and 6, and between

the latter is an annular chamber 8 which is accessible through the inner inlet or supply opening 7. The outer shell 5 is imperforate and the inner shell 6 is formed with rows or a plurality of openings 9 through which the fumes and moisture of a suitable germicide, salt, chemical or chemical compound passes to the interior of the mouthpiece or inner surface of the shell 6. The inner side of the inner terminal of the outer shell 5 is formed with screw-threads 10 to receive corresponding screw-threads 11 on the outer side of an annular flange 12 projecting from the center of a head 13 of a combined chamber closing and attaching plug or union 14 having an interiorly and exteriorly screw-threaded neck 15. The central position of the flange 12 relatively to the head provides outer and inner annular shoulders or ledges 16 and 17 against which the inner ends of the shells 5 and 6 are adapted to respectively abut when the plug 14 is applied. The plug head 13 is also formed with an inner perforated partition or septum 18 of the form ordinarily used in the mouthpieces of telephone transmitters to protect the diaphragm. The screw-threads on the exterior and interior of the plug neck 15 are to adapt the mouthpiece for attachment over a screw collar or analogous device, or within a screw-threaded opening 19, as shown by Fig. 1. The threads on the neck 15 are right-hand, and the threads 11 of the flange 12 are left-hand, to avoid loosening the plug from the shells 5 and 6 and unsealing the chamber 8 when detaching the mouthpiece as a whole, or to permit the detachment and attachment of the shells relatively to the plug to refill or recharge and reapply the chamber 8 without detaching the plug from the transmitter or other device to which the mouthpiece is applied. It will be seen that the flange 12 tightly closes the inner portion of the chamber 8 and all fumes and moisture from the germicide are caused to pass through the openings 9 of the inner shell to the interior of the orifice of the mouthpiece.

The parts of the plug 14 are of integral formation, and said plug as an entirety is preferably formed of vulcanized rubber, but metal, compressed fiber or other suitable material may be used for this purpose.

The antiseptic disinfecting or deodorizing salt, chemical compound, or germicide disposed in the chamber 8 may be of any well

known or other form, but it is preferred that it be sufficiently humid to permit moisture thereof to pass through the openings 9 to the inner surface of the shell 6 to hold such 5 germs as may not be destroyed or killed by the fumes and prevent inhalation thereof by the user of the mouthpiece. The greater portion of the germs, however, will be destroyed by the fumes of the disinfectant or 10 germicide passing to the interior of the orifice. The mouthpiece may be easily cleaned from time to time by thoroughly wiping the interior wall or inner shell and exposed portions of the plug including the partition or 15 septum 18.

Among the many structural advantages of the improved mouthpiece the more important are the convenience in charging the chamber 8 and the positive sealing of the 20 charging inlet of said chamber by the flange 12 of the plug 14, and the facility in attaching and detaching the mouthpiece as a whole through the medium of the plug without exposing or unsealing the chamber 8 25 and the capability of detaching the shells 5 and 6 as a unit and exposing the chamber at its inner extremity for recharging the same without disturbing the plug.

It will be understood that the dimensions 30 and proportions of the mouthpiece may be varied at will.

What is claimed is:

1. In a sanitary mouthpiece, inner and outer shells having a chamber therebetween 35 open at its inner extremity, the inner shell being perforated and the chamber containing a moist germicide, and a plug having a closing flange for entering the inner open end of the chamber between the shells and a 40 screw-threaded neck for attaching the mouthpiece.

2. In a sanitary mouthpiece, inner and outer shells having a chamber between them and formed continuous at their outer portions and spaced at their inner extremities 45 to provide a charging opening, the inner shell being perforated and the chamber filled with a moist germicide, and an attaching plug having means for closing the charging 50 opening and extending inwardly between

the shells and fully sealing the inner ends of the shells.

3. In a sanitary mouthpiece, inner and outer shells having a chamber between them with a charging opening at its inner extremity, the inner shell being perforated and the chamber filled with a suitable germicide, the inner side of the inner end of the outer shell having screw-threads, and a plug having an exteriorly threaded annular flange 55 to fit in and close the inner extremity of the chamber and also provided with a threaded attaching neck, the threads of the shell and flange and neck being left and right.

4. In a sanitary mouthpiece, inner and outer shells having a germicide chamber therebetween open at its inner extremity for charging purposes, the inner shell being perforated, and a combined sealing and attaching plug having an annular sealing flange 60 extending from one end thereof into the open extremity of the chamber and a shoulder on each side of the flange to abut against the inner ends of the shells, an attaching neck being provided at the opposite end of 70 the plug and a perforate partition within the latter.

5. In a sanitary mouthpiece, inner and outer shells having a chamber formed between them with a charging opening at the inner ends of the shells, the inner shell being perforated and the chamber normally filled with a germicide, and an attaching plug having means for removably closing the said charging opening of the chamber. 80

6. In a sanitary mouthpiece, inner and outer shells having a germicide containing chamber therebetween provided with a charging opening at the inner ends of the shells, the inner shell being perforated, and an attaching plug having means to enter and seal the said charging opening and to abut against the inner ends of the shells. 90

In testimony whereof I have hereunto set my hand in presence of two subscribing 95 witnesses.

WILLIAM W. WOODRUFF.
